PAPER DISPENSING RECEPTACLE

Filed May 23, 1931

INVENTOR

Charles W. Spain

BY Joseph K. Schaeffer
ATTORNEY.

UNITED STATES PATENT OFFICE

CHARLES W. SPAIN, OF HARTFORD, CONNECTICUT

PAPER DISPENSING RECEPTACLE

Application filed May 23, 1931. Serial No. 539,443.

This invention relates to containers for paper articles and particularly to a container or receptacle for displaying and dispensing goods comprising sheets of paper contained 5 therein in suitable layers.

An object of the present invention is to provide a receptacle that will enclose and protect the goods, permit inspection of the goods and also enable the goods to be withdrawn separately and individually from the receptacle without disturbing the remainder of the goods.

A further object of the invention is to provide a receptacle of paper, particularly 15 formed for retaining sheets of cleansing tissue and enabling packages thereof to be shipped in fully protected condition but permitting inspection of the goods when displayed for sale, the goods being adapted to be withdrawn individually when a readily separated portion of the receptacle is removed.

And finally it is an object of the invention 25 to provide a receptacle with a removable portion, removal of which converts an opening or openings through which the goods may be seen and inspected into an opening through which the goods may be withdrawn in small quantities or individually.

One feature that enables me to accomplish 30 the above objects is that a receptacle of paper or other suitable material is provided of boxlike form, across the front surface of which may be provided separated narrow 35 elongated openings in alignment with each other, the central portion of this face of the receptacle between these openings being adapted to be removed so that an enlarged 40 central opening may be formed joining the spaced narrow openings.

With the above and other objects in view, my invention consists in the features of construction and operation set forth in the following specification and illustrated in the 45 accompanying drawing.

In the accompanying drawing annexed hereto and forming a part of this specification, I have shown my invention embodied in a receptacle specially designed for thin 50 and flexible sheets of cleansing tissue formed

of paper and closely packed in folded condition, but it will be understood that the invention can be otherwise embodied and that the drawing is not to be construed as defining or limiting the scope of the invention, 55 the claims appended to this specification being relied upon for that purpose.

In the drawing:

Figure 1 shows a perspective view of a receptacle made according to the present invention;

Fig. 2 shows an outline of the receptacle before folding and pasting; and

Fig. 3 shows an end view with a sheet being withdrawn.

In the above mentioned drawing I have shown but one embodiment of the invention which is now deemed preferable, but it is to be understood that changes and modifications may be made within the scope of the 70 appended claims without departing from the spirit of the invention.

Briefly, and in its preferred aspect, my invention may include the following principal parts: A rectangular box-like receptacle 75 preferably having its sides and ends retained permanently in position as by pasting in the usual manner; second, narrow cut-out portions on one of the larger surfaces through which the goods are visible and may be inspected; and third, a partially separated portion of the latter surface intercepting the above openings and which, when removed, provides an opening joining the narrow cut-out portions and enables a user to manually 80 grasp and withdraw one or more of the sheets contained within the receptacle.

Referring more in detail to the figures of the drawing, I provide a box-like receptacle 10 preferably formed of a single sheet of material having its end and side flaps 11 secured in overlapping and closed positions, as by pasting in the usual manner. The cover flap 12 may be folded within the receptacle and retained by pasting if desired. 90 As the particular form of these portions of the box or receptacle 10 constitutes no part of the present invention they will not be further described. The receptacle may be made of paper or other suitable material and 100

of such size that it will closely fit the goods to be displayed and dispensed.

Cut into one of the front or wider surfaces of the receptacle 10 are narrow openings 13, one on each side of the center, the outer ends of these openings terminating at opposite edges of the surface in which the openings are cut. These openings 13 are in alignment with each other and of suitable width 10 to permit ready withdrawal of the sheets 14 in a manner presently to be described.

In the central portion of the surface in which the openings 13 are cut is a portion 15 partially separated or cut so that it may 15 be easily torn away about its periphery or outline. The form of this opening provided by tearing away the material within the outline of this portion 15 is such that it will accommodate the fingers of a user 20 grasping and withdrawing the sheets 14 from the receptacle 10. The lateral extensions of this portion 15 adapted to be torn out extend to and intercept the lateral narrow openings 13 referred to above.

25 With the portion 15 in place prior to its being torn out, the goods 14 are fully protected from falling out and may be seen through the lateral narrow openings. With this portion 15 in place the goods 14 may be 30 shipped within the receptacle 10 and placed on display upon a counter or shelf. The purchaser receives the receptacle 10 with the portion 15 in place, the portion thus acting as a seal to indicate the goods are in the 35 same condition as when packed. Upon tearing out the central portion 15 ample space is provided for the user to grasp the goods individually, and through the opening formed by tearing away the portion 15 and 40 the lateral narrow openings 13 the goods may be withdrawn singly or in pairs. This may be done without disturbing the unused portions of the goods remaining within the receptacle.

45 To indicate the place to start the tearing away of the central portion 15, arrows or triangles 16 may be printed upon this portion, together with any desired information as to methods of using the contents.

50 What I claim is:

1. A receptacle comprising a box-like enclosure having lateral narrow openings within one of its surfaces, and a partially cut portion of said surface centrally disposed 55 and intercepting said lateral openings whereby said central portion may be readily detached to provide an opening extending longitudinally across the face of the receptacle formed of a single piece of foldable material through which goods within the receptacle may be individually withdrawn.

2. A receptacle comprising a box-like enclosure having lateral narrow openings within one of its surfaces, and a portion of said surface centrally disposed and of material-

ly greater width than said openings intercepting said lateral openings whereby said central portion may be readily detached to provide an elongated opening extending from one end to the other of the receptacle, the central portion enabling a user to grasp and individually withdraw the goods contained within the receptacle.

3. A receptacle comprising a boxlike enclosure having separated narrow openings formed within one of its surfaces, the outer ends intercepting the end walls of the receptacle, and a relatively wider portion of said surface centrally disposed and intercepting said spaced openings partially cut from said receptacle whereby said central portion may be readily detached to provide a continuous opening extending from end to end of the receptacle formed of a single piece of foldable material through which goods within the receptacle may be individually withdrawn.

4. A receptacle for individually folded sheets of flexible material comprising a boxlike enclosure closely fitting the material in folded form and having separated narrow openings within one of its surfaces, the outer ends of which extend to the end walls of the receptacle, and a relatively wider portion of said surface centrally disposed and intercepting said spaced openings, said central portion being partially cut from said receptacle whereby said portion may be readily detached to provide a continuous opening extending from end to end of the receptacle through which individual pieces of said folded material may be grasped and separately withdrawn from the receptacle.

In testimony whereof, I hereto affix my signature.

CHARLES W. SPAIN.
